Lincoln Johnson

UNITED STATES PATENT OFFICE.

GEORGE A. PATTBERG, OF SAN LEANDRO, CALIFORNIA, ASSIGNOR TO ELIZABETH PATTBERG, OF SAN LEANDRO, CALIFORNIA.

CAN OPENER.

Application filed June 15, 1922. Serial No. 568,504.

To all whom it may concern:

Be it known that I, GEORGE A. PATTBERG, a citizen of the United States, and a resident of the city of San Leandro, county of Alameda, State of California, have made a new and useful invention, to wit, Improvements in Can Openers; and I do hereby declare the following to be a full, clear, concise, and exact description of the same.

10 This invention relates particularly to an improved "scissor" type of can opener.

The object of the invention is to provide a pair of cross-pivoted handle members having an engaging and cutting means thereon 15 for removing the sealed tops of cans or cutting sheet metal.

A further object of the invention consists in providing a device that will be superior 20 in point of simplicity, inexpensiveness of construction, positiveness of operation and facility and convenience in use and general efficiency. Other objects and advantages will appear as this description progresses.

In this specification and the annexed 25 drawings, the invention is illustrated in the form considered to be the best, but it is to be understood that the invention is not limited to such form, because it may be embodied in other forms; and it is also to be 30 further understood that in and by the claims following the description, it is desired to cover the invention in whatsoever form it may be embodied.

In the accompanying one sheet of drawings,

Fig. 1 represents a plan view of a can opener constructed in accordance with my invention.

Fig. 2 is a side elevation of Fig. 1.

40 Fig. 3 is an enlarged detail view of the can opener from the under side.

In detail, the construction illustrated in the drawings comprises the members 1 and 2, cross-pivoted at 3 to provide the respective extended and projecting ends 4 and 5. Each of the members 1 and 2 are preferably stamped from a light gauge of sheet metal, the handle portion 6 of the member 1 being rolled over to present a substantially curved 50 exterior and the corresponding portion 7 of the opposite member 2 being provided with a series of notches or undulations 8 intended to receive the fingers. An externally flanged cover 9 is adapted to lie on the upper face

of the handle 2 and is provided with an internal flange, through which the pivot pin 3 is adapted to pass. A spiral spring 10 is mounted within the interior of the cover 9 and extends around the pivot 3, an end of said spring being secured in the handle member 2 while the opposite end 11 of the spring 10 projects through the cover 9 and slidably engages the interior face of the handle 6 of the member 1. The spring thus functions to keep the respective handle members 1 and 2 spread apart and materially aids in the can opening operation.

In order to operate the device, the handles 6 and 7 would be placed in the hand, palm up, so that the thumb might engage the rounded handle 6 on the member 1 and the respective fingers lie, one each, in the grooves 8 provided on the handle 7 of the member 2. Experiments have proven that the most efficient operation of the can opener is obtained 75 by operating the handles with the palm up and the formation of the respective handles, in the manner described, thus causes the instrument to be naturally grasped by the hand in the correct operating position. Adjacent the extended end 4 of the handle member 1, a serrated projection 12 is rigidly secured thereon, said projection comprising a short cylindrical member formed of a high grade of tool steel and with a predetermined 80 number of teeth cut around its periphery. The edge 13 of the extended end 4 is cut on the arc of a circle and is slightly serrated or knurled.

The extension 5 on the handle member 2 90 has a plate or link 14 pivoted thereto by the pin 16, said pin having a depending or projecting head 17 thereon, substantially of the same length as the serrated projection 12. The axes of the pin 16 and serrated 95 projection 12 are spaced on an equal radius from the pivot 3. The end of the plate 14 has a laterally projecting shoulder 18 formed integrally therewith, the inner edge 19 of said shoulder being cut or formed on the 100 arc of a circle of the same radius as that of the end edge 13 on the extension 4 of the handle member 1.

A shouldered button 20 is rigidly secured on the upper side of the plate 14 and to which a cutting blade or knife 21 is secured by the screw 22. The blade 21 is adapted to be received in a slot or depression formed

on the edge of the plate 14 so that the end of the said knife will depend from and extend below the under face of the plate 14. The knife 21 is provided with a pointed end 5 23 to facilitate its penetrating through a metal can and has sharpened edges.

The construction of the can opener is such that the handles 6 and 7 of the members 1 and 2 may be positioned in substantial parallel alignment, in close proximity, so that the pivoted plate 14 may be partially rotated to permit the hook-shaped projection 18 on the said plate being passed over and around the curved edge of the extended end 4 of the handle member 1. By releasing the pressure of the hand on the handles, the spring 10 will tend to expand and force the handle members apart. Spreading action is prevented by the hook-shaped end 19 of the link 14 engaging the curved edge 13 on the opposite handle member to thus hold the respective parts in closed, inoperative position.

The tool is operated by placing the handles 6 and 7 in hand with the palm up so that the fingers are securely placed in the notches 8 of the handle member 2. By squeezing the handles together against the tension of the spring 10, the locking contact 25 between the hooked end of the plate 14 and end 13 of the handle member 1 would be broken, permitting the locking means to be pivoted free of engagement. In the opened position, the ends 4 and 5 of the respective 30 handle members 1 and 2 would be placed over the top of a can to be opened so that the depending projections 12 and 17 on the said respective members might be placed in-

to engagement with the periphery or side of the can. In this position, a downward pressure would be applied to the button head 20, forcing the knife 21 into and through the can material. The fingers of the hand would then be closed to thus draw the ends 4 and 5 of the handle members together and thus impart a short movement of 40 the knife 21. Upon releasing the pressure on the handles, the spring 10 would force the same apart into a spread position to permit a repetition of the intermittent closing 45 together of the handles by the fingers of the operator, thus continually advancing and drawing the knife 21 through the can material for any length of cut desired.

Having thus described this invention, 50 what I claim and desire to secure by Letters Patent is:—

A can opener comprising, a pair of opposed handle members pivoted together; spring means for separating said handle members; a plate pivotally mounted on an end of one of said handle members, opposite the handle portion thereof, having a lateral projection thereon to detachably engage the end of the other handle member to hold the pair of handle members together; and cooperative can cutting means on the ends of the handle members, opposite the handle portions thereof.

In testimony whereof, I have hereunto set 70 my hand at San Francisco, California, this 19th day of May, 1922.

GEORGE A. PATTBERG.
In the presence of—
LINCOLN V. JOHNSON.
